ABSTRACT: An apparatus for actuating shuttles in a multi-shuttle loom in which a guide plate having a U-shaped slot cooperates with a pin secured to a rack and pinion driving mechanism to give shuttles a reciprocating movement with respect to the batten of a loom by converting forces acting in the direction of movement of the batten into forces in a perpendicular direction to the batten's movement.

APPARATUS FOR ACTUATING SHUTTLES IN A MULTI-SHUTTLE LOOM

This application is a continuation-in-part of application Ser. No. 597,818, filed Nov. 29, 1966, now abandoned.

The present invention relates to apparatus for imparting a reciprocating motion, transverse to the direction of movement of the batten, to shuttles which follow guide tracks along the batten of a multishuttle loom.

In multishuttle looms for the manufacture of narrow woven fabrics, such as ribbons, arched shuttles are movably attached to the battens. As the battens move toward and away from the loom body in the direction of the warp thread, the shuttles move back and forth along the batten in the direction of the weft thread. The problem of transmitting these two reciprocating motions, which are directed perpendicularly to each other, to the shuttles has long been a difficult problem in the art. Various complicated power transmission and guiding mechanisms have heretofore been employed.

Usually the movement of the batten in the warp thread direction has been transmitted by a crankshaft and connecting rods. To move the shuttles along the batten in the direction of the weft thread, moving elements attached to the shuttles have been actuated by means of eccentric gears, transmission levers and transmission belts, or by means of an eccentric drum and transmission lever. This has made the construction of the loom very complicated and costly, since each of the mechanical movements has to be accurately coordinated with the others. Wear on all of the moving parts is great and the power requirements of such a loom are large.

The object of this invention is to provide an apparatus for transmitting the desired motion to the shuttles in a simple manner, without the use of complicated transmission elements and with minimum power requirements.

Another object of this invention is to provide a novel apparatus for the actuation of shuttle movement in a loom by the use of a transmission mechanism including a U-shaped guide which translates forces from the reciprocating motion of the batten into a reciprocating force in a direction perpendicular to the movement of the batten to drive the shuttles.

Other objects and advantages of the present invention will be apparent from the following detailed description of an embodiment of the invention and from the accompanying drawings, in which:

FIG. 1 is an enlarged, fragmentary, horizontal section showing cam means and rack and pinion means for actuating the shuttles of the apparatus;

FIG. 2 is an enlarged side view taken on line E—E of FIG. 3 looking in the direction of the arrows with some parts shown in vertical section; and

FIG. 3 is a fragmentary side elevation of the portion of the apparatus shown in FIG. 1, with part of the cam means shown in vertical section taken on line G—G of FIG. 1 and looking in the direction of the arrows.

In the drawings, in which like reference numerals designate like parts throughout, the loom body of the multi-shuttle loom is indicated at 9 (FIG. 2). Spaced from the loom body 9 and extending along the front of the loom is the breast support 8. The batten, generally indicated at 7, lying in the space between the loom body 9 and the breast support 8, is a massive elongated channular member, having an upright web 13 and upper and lower legs 14 and 15 which extend horizontally in the forward direction toward breast support 8, as shown in FIG. 2.

The batten 7 is mounted for reciprocating movement transversely of its length in a horizontal plane toward and away from the loom body 9. The means effecting this movement of the batten 7 is best shown in FIG. 2.

A disc wheel 12, mounted for rotation at the end of a loom body 9, has one end of a crankshaft 11 pivotally attached to the wheel 12 at an off center position. The other end of the crankshaft 11 is pivotally connected to the batten 7 through a connecting link member 17 rigidly secured to the batten. The rotation of the wheel 12 imparts reciprocating motion to the batten 7 through the crankshaft 11 and connecting link 17. The batten's reciprocating movement toward and away from the loom body 9 is in the direction of the warp thread

or the loom product.

Referring now to FIGS. 2 and 3, the web 13 of the batten 7 is seen to be provided with an elongated aperture therethrough which provides a passage through which a flat guide plate 1, to be described later, extends. The aperture 16 is sufficiently large to allow the reciprocating movement of the batten 7 to take place without the batten touching the guide plate 1.

Referring now to FIG. 1 showing the transmission mechanism of the apparatus viewed from above, the guide plate 1 is seen to be rigidly attached at one of its ends by bolts 8a directly to the breast support 8 of the loom and at its other end to the loom body 9 by bracket 19. The guide plate 1 lies in a plane normal to that of the web 13 of the batten 7 and extends through the aperture 16.

A U-shaped guide slot 10 is formed in the guide plate 1 with the base 10b of the U toward to the loom body 9 and its legs extending toward the breast support 8 and terminating in rounded ends 10a and 10c. A pin 2 extends vertically through the slot 10, with its upper and lower ends extending above and below the horizontal surfaces of guide plate 1. The curved portions of the U-shaped slot provide cam surfaces for the pin 2, which moves around the U as the transmission mechanism operates in a manner to be described. The pin 2 has a roller 3 mounted thereon to rotate about the axis of the pin 2 preferably by some anti-friction means such as the ball bearings shown.

The upper and lower ends of the pin 2 are rigidly secured to laterally extending upper and lower bars 6, as shown in FIGS. 2 and 3. The pin 2, through the bars 6 actuates a rack and pinion mechanism mounted on the batten 7 and about to be described.

Referring to FIGS. 2 and 3, the elements of the rack and pinion drive are shown to be positioned inwardly of the legs 14 and 15 of the batten. Slideways for slidably receiving extensions of the racks are provided along the length of the batten 7 by spaced angle bars 4 and 5. The bars 5 are secured to each leg of the batten 7 adjacent the outer end thereof and extend inwardly therefrom. The angle bars 5 are reinforced by exterior spaced bracing members 18. The angle bars 4 are mounted on the web 13 in spaced parallel relationship with respect to the angle bars 5. The spaced opposed surfaces of the pairs of parallel bars 4 and 5 provide upper and lower guide tracks along the upper and lower legs 14 and 15 respectively of the batten 7.

As stated above and shown in FIGS. 2 and 3, the pin 2 is connected at its upper and lower ends to laterally extending upper and lower bars 6 which reciprocate with respect to the inner surface of the batten web 13 and follow the motion of the pin 2. The bars 6 are also secured, for example, by vertical pins to upper and lower bars 42a forming extensions of elongated toothed racks 42 which extend along between the slideways formed on the batten 7 between the guide bars or rails 4 and 5.

Referring to FIG. 3, showing the shuttle drive, it will be clear that since the bars 6 are suitably connected to the rack extensions 42a, the bars 6 and the racks 42 will move together along the slideways 4, 5 when the pin 2, secured to bars 6, moves.

At spaced positions along the batten 7 to the right of the plate 1 as seen in FIG. 3 gears 40 are mounted in housings 43. These gears are in mesh with the teeth 44 of the racks 42 to be rotated back and forth as those racks reciprocate. Such housings and gears are positioned with sets of gears 40 in mesh with both the upper and lower racks.

Sets of shuttles 41 are positioned in an upper row for slideable movement in the housings 43 adjacent the upper array of gears 40 and in a similar lower row. Each shuttle carries a row of teeth 45 which mesh with the teeth of the gears 40. Thus, when the gears 40 are turned by the motion of racks 42, the shuttles are slid linearly in a direction opposite to the direction of movement of the rack 42. When the movement of the racks 42 is reversed, the shuttle movement will likewise be reversed.

The mode of operation of the apparatus is much simpler than that of known actuating devices. As the wheel 12 rotates, causing the crankshaft 11 to move in and out, a sliding reciprocating motion in the warp direction is imparted to the batten 7. As the batten moves toward and away from the loom body 9, the pin 2 is moved likewise, but the pin being constrained by the guide plate 1 is also caused to follow the path of the U-shaped slot 10 through which the pin extends. The guide plate 1 remains stationary, being rigidly attached to the loom body 9 and to the breast support 8.

The movement of the pin is as follows. Starting from the position 10a of FIG. 1 where the batten 7 is at its position nearest the breast support 8 and farthest from the loom body 9, as the batten 7 moves toward the loom body 9, pulled by crankshaft 11, the roller 3, carried by the pin 2, is caused to move along the curved camming surfaces of the slot 10. As the batten 7 moves to its position farthest from the breast support 8 and nearest to the loom body 9, the roller 3 is carried down the arm of the U-shaped slot 10 to the base of the U. The momentum generated during its motion carries the roller 3 and the pin 2 past the center point 10b at the base of the U, preventing the pin 2 from returning to the position 10a so that as the batten 7 returns to the position of FIG. 1, the roller 3 travels up the other arm of the U carrying the pin 2 to position 10c. Thus the pin has been moved transversely to the direction of motion of the batten 7 and due to the system of coordinates fixed with respect to the batten 7, the pin 2 has moved in a straight line along the batten 7, that is, in the direction of the weft thread. The distance the pin 2 has moved is clearly equal to the width of the U measured from point 10a to point 10c. Repeating the cycle causes the pin 2 to return around the U-shaped slot 10 to its original position, 10a.

Since the pin 2 is engaged at its upper and lower ends with the bars 6, these bars are moved along the batten 7 with the pin and the same distance as the pin. The bars 6 in turn push and pull the upper and lower racks 42 with them along the guide tracks of the batten 7 as the pin 2 moves reciprocatingly back and forth along the batten between the positions 10a and 10c. The gears 40 are turned by the racks and their rotation causes the shuttles 41 to fly back and forth along the batten 7 carrying their thread through the shed in the weft direction.

The reciprocating motion of the batten 7, toward and away from the loom body 9 thus provides the desired movement in the direction of the warp thread and also, through the transmission mechanism described, actuates the shuttles to move in the weft thread direction.

Though the eccentric drive of the batten and the reciprocating drive of the shuttles has been shown at only one end of the batten, such drives would be positioned at both ends for proper operation.

5 In a modification of the invention, the guide element may be formed from a bar bent into the shape of a U, in which case the pin 2 would be replaced by a slide which would follow the curve of the U-bar just as the pin moves around the U-slot to actuate the shuttles.

10 Other modifications and variations of the apparatus disclosed herein may well suggest themselves to those skilled in the art without departing from the spirit and scope of the invention.

Having described my invention what I claim as new and 15 desire to obtain Letters Patent for is:

I claim:

1. Apparatus for controlling movement of shuttles in a loom, comprising a movable batten, a plate fixed to the loom and having a U-shaped slot therein, a pin positioned in the 20 slot, means for moving the batten so as to cause the pin to follow the contour of the U-shaped slot in the plate and to travel a corresponding path, and means movable by the pin for causing the loom shuttles to be actuated.

2. Apparatus according to claim 1 in which said U-shaped 25 slot has its legs extending in the direction of movement of the batten.

3. Apparatus in accordance with claim 1 wherein the means movable by the pin for causing the loom shuttles to be actuated include a movable carrier for supporting and moving a 30 shuttle, and means actuated by the pin for causing the carrier to reciprocate and thereby move the shuttle.

4. Apparatus in accordance with claim 3 wherein the shuttle reciprocating means includes a rod having teeth thereon and the movable carrier is provided with gears which mesh with 35 and are rotated by the teeth on the rod, whereby the shuttles are actuated when the rod is moved with respect to the gears.

5. Apparatus according to claim 1 wherein a roller is mounted concentrically and rotatably on the pin, providing 40 rolling contact with sides of the slot as the pin travels.

6. Apparatus according to claim 1 wherein the means for moving the batten comprises a drive wheel, a crankshaft pivotally attached at one end to the wheel at a point remote from the center of the wheel and pivotally attached at its other end to the batten for converting rotary motion of the wheel 45 into reciprocating movement of the batten.
